UNITED STATES PATENT OFFICE

2,438,988

PLURAL SECTION DISTILLATION COLUMN
WITH TOP FEEDWilliam F. Barthel, College Park, Md., assignor to
the United States of America as represented by
the Secretary of Agriculture

Application January 12, 1945, Serial No. 572,503

5 Claims. (Cl. 202—154)

(Granted under the act of March 3, 1883, as
amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a distillation apparatus, and in particular to an apparatus which will produce rapid evaporation of liquids and solvents.

In the usual procedure for the concentrations of solutions or the removal of liquid solvents, the original solution is heated in a vessel either at atmospheric pressure or reduced pressure and the volatile portion vaporized by boiling. In such cases, the thickness of the liquid layer is such that the rate of evaporation is slow, and as the solution becomes more concentrated, the rate of evaporation becomes yet slower. Thus, a long period of heating is required. The solute must be stable to the heat treatment necessary to remove the solvent, if the procedure is to be employed without harm to the solute. Many materials, however, decompose during such a procedure.

If the layer of the solvent is reduced to a minimum, the rate of evaporation greatly increased, and the solute quickly removed from the heated area, the chances of decomposition are substantially eliminated, and this invention has among its objects provision of an apparatus which will accomplish these functions.

The apparatus is diagrammatically illustrated in the single figure of the accompanying drawing.

In the drawing, the principal element of the apparatus is an upwardly extending tubular member or column 11 heated by means of a surrounding heat jacket 12 provided with a heating fluid inlet 13 and an outlet 14 in a conventional manner. The inner surface of the column 11, over which the liquid being distilled flows as a layer, is provided with laterally extending corrugations, preferably formed by constructing the column itself as a connected row of hollow spheres in the manner illustrated. There is no communication between the heating fluid and the interior of the column. The structure thus provides means for heating the column independently of the temperature and flow over the internal surface of the column of the liquid being distilled.

The solution or distillation liquid enters the column at the top from a supply tank 15 and the rate of flow may be regulated by an adjustable cut-off valve 16 in the line connecting the supply

2

tank to the column. As the liquid descends, it adheres to the internal surface of the column by capillary attraction, the corrugations causing it to spread thinly and not flow too rapidly down the surface.

As shown, the column is divided into an upper section 17 and a lower section 18 by a valve, preferably a ball 19, which seats on a tube 20 connecting two of the spheres forming the column. The purpose of this is to prevent too great a rush of liquid through tube 20, thus to aid in accomplishing an even distribution of the liquid on the internal surface of the column. This type of valve operates automatically when arranged in the manner shown, since gas pressures develop under the ball 19 in excess of that above, due to upward movement of the gas, causing the ball to bob on its seat and intermittently release liquid entrapped above it.

10 The upper section 17 of the column acts as a boiler and the lower section 18 as a stripper of the more concentrated liquid. More sections may, of course, be provided.

15 As the liquid flows downwardly, the distillate is removed and the residue is finally deposited in the receiver 21.

20 The distillate is carried through pipes 22 and 23 connected to the upper ends of the sections 17 and 18, respectively, these pipes communicating with an expansion chamber 24. Any droplets of the liquid which may be carried over with the distillate settle to the bottom of the expansion chamber and flow back to the column through the pipe 23 which is connected to the lower portion of the expansion chamber.

25 From the expansion chamber, the distillate gas passes through pipe 25 to a conventional condenser 26 from whence the condensate is recovered through pipe 27. Low pressure distillation is accomplished by evacuating through the condenser in a conventional manner.

30 As an example of use of the apparatus, a solution of 10 percent total pyrethrins in nitromethane was passed through the apparatus under a 40 mm. vacuum. The upper and lower sections were heated with steam at 100° C. The nitromethane evaporated at this low temperature without decomposing the pyrethrins, giving a 98 percent concentration of the pyrethrins in the receiver. Any given quantity of pyrethrins was never in the still more than a few minutes, the pyrethrins passing through the heated column to the cool receiver in that time. It would take approximately 10 times as long to remove 35 the nitromethane in a conventional still and the

pyrethrins would be subjected to the higher temperatures of the conventional still for the entire time required for distillation.

Having thus described the invention, what is claimed is:

1. Distillation apparatus comprising an upwardly extending tubular column, means for introducing distillation liquid into the upper end of the column, said column being so constructed that a film of the liquid is spread over its internal surface as it descends the column and being divided into an upper section and a lower section with a valve between the sections which traps liquid in the upper section and intermittently opens to allow the liquid to flow into the lower section, and means for heating the column independently of the temperature and flow over the internal surface of the column of the liquid being distilled.

2. The apparatus of claim 1, characterized in 20 that the valve operates automatically.

3. The apparatus of claim 1, characterized in that the valve comprises a ball resting on a seat and is raised from its seat by excess gas pressure developed underneath it.

4. Distillation apparatus comprising an upwardly extending tubular column, means for introducing distillation liquid into the upper end of the column, said column being so constructed that a film of the liquid is spread over its internal surface as it descends the column and being divided into an upper section and a lower section with a valve between the sections which traps liquid in the upper section and intermittently opens to allow the liquid to flow into the lower section, an expansion chamber, pipes leading from the upper ends of the sections for carrying distillate gases into the expansion chamber, one of said pipes being connected to the lower portion of said expansion chamber to carry any liquid which settles in the expansion chamber back into the column, and means for heating the column independently

of the temperature and flow over the internal surface of the column of the liquid being distilled.

5. Distillation apparatus comprising an upwardly extending tubular column, means for introducing distillation liquid into the upper end of the column, said column being so constructed that a film of the liquid is spread over its internal surface as it descends the column and being divided into an upper section and a lower section 10 with a valve between the sections which traps liquid in the upper section and intermittently opens to allow the liquid to flow into the lower section, and a jacket provided with a heating fluid inlet and a heating fluid outlet surrounding the column with no communication between the heating fluid within the jacket and the interior of the column.
